Primary Examiner — Mark A Goodwin(74) *Attorney, Agent, or Firm* — IpHorgan Ltd.(57) **CLAIM**

The ornamental design for an optical type sorter, as shown and described.

DESCRIPTION

FIG. 1 is a perspective view of an optical type sorter showing the new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines are for illustrative purposes only and form no part of the claimed design.

1 Claim, 5 Drawing Sheets(56)
